DESIGN FOR A NASAL DOUCHE

Ralph H. Osmun, Dayton, Ohio

Application September 18, 1943, Serial No. 111,155

Term of patent 14 years

To all whom it may concern:

Be it known that I, Ralph H. Osmun, a citizen of the United States of America, residing at Dayton, in the county of Montgomery, State of Ohio, have invented a new, original, and ornamental Design for Nasal Douche, of which the following is a specification, reference being had to the accompanying drawing, forming a part thereof in which the figure is a view in perspective showing my new design of a nasal douche. The other side of the article is substantially like the side shown.

I claim:

The ornamental design for a nasal douche, substantially as shown and described.

RALPH H. OSMUN.
